[57] CLAIM

The ornamental design for a pop up magnifier, as shown and described.

DESCRIPTION

FIG. 1 is a top view of the pop up magnifier with the magnifier extended showing my new design;

FIG. 2 is a bottom plan view thereof;

FIG. 3 is a left side view thereof, the right side being a mirror image thereof;

FIG. 4 is a rear elevational view thereof;

FIG. 5 is a front elevational view thereof;

FIG. 6 is a top view of the pop up magnifier with the magnifier retracted;

FIG. 7 is a bottom view of the retracted pop up magnifier;

FIG. 8 is a left side of the retracted pop up magnifier, the right side view being a mirror image thereof; and,

FIG. 9 is a front elevational view of the retracted pop up magnifier.
